UNITED STATES PATENT OFFICE

JOHN P. LYNN, OF CHICAGO, ILLINOIS, ASSIGNOR TO DUR-O-LITE PENCIL COMPANY, OF CHICAGO, ILLINOIS, A CORPORATION OF ILLINOIS

PENCIL

Application filed March 22, 1928. Serial No. 263,665.

This invention relates to a pencil having mechanical means for propelling, repelling, or expelling a lead through its tip portion. The mechanism employed is of the screw-operated type actuated by rotation of one part relative to another.

The principal objects realized by this invention are simplicity in construction and operation, expulsion of the lead following the exhaustion of its serviceable portion; and protection to the operating parts against accident or tampering incident to usage. In accomplishing these purposes, I associate with a pencil body part a separable operating part or unit forming, by preference, the tip of the pencil. In response to relative rotation between the body part and this operating part or unit, a carrier which clutches a lead may be propelled longitudinally in one direction or the other, between fixed stops, to extend or retract the lead through the tip of the pencil. Within the range required for this limited feed of the lead, the pencil operation is substantially frictionless, as the carrier and lead are propelled as a unit. If it is desired however to extend the lead through the pencil tip to a greater extent than is permitted by the limited movement of the carrier, continued relative rotation of the parts will effect an adjustment of the lead relative to the carrier, which adjustment will be attained by a distinct increase in resistance to rotation of the parts. In addition to the above peculiarities of operation, I so construct the carrier that the lead to be clutched thereby may be introduced thereto from either of two opposite ends, i. e., that is through the tip end of the pencil or through the end of the operating unit which is opposite thereto.

These and other objects of my invention will more clearly hereinafter appear in the specification and claims, taken in conjunction with the accompanying drawings which illustrate a suggestive embodiment of the present invention in the manner following:

Figure 1 is a longitudinal section taken centrally through the pencil, a portion centrally of its length being broken away to

condense the view, and the lead carrier being shown in its extreme upper position;

Fig. 2 is a similar view of the lower pencil end with the lead carrier advanced to its lowermost position;

Fig. 3 is a similar view with the propeller advanced through the carrier so as to expel a lead from the pencil;

Fig. 4 is a detail in elevation of the pencil head, with a portion broken away to exhibit the parts in section;

Fig. 5 is a detail in elevation of the lower end of the lead carrier, showing, in section, the corresponding end of the surrounding tube;

Fig. 6 is a transverse section taken on line 6—6 of Fig. 1; and

Fig. 7 is a view in elevation of the lead carrier per se.

In the present pencil I combine separably with a body part A a relatively rotatable part such as the tip B. The body is provided with a slotted axial bore 8 through which may slide non-rotatably a screw means such as a screw-threaded propeller 9 having a head 10 at one end thereof. This bore in the body extends upwardly from its lower end for a distance sufficient to accommodate the propeller throughout its entire range of movement. In its lower region the bore may be slightly widened to accommodate a bushing 11 wherein is received the enlarged end or head 12 of a tube 13 which extends down within the tip to present its lower end against a stop shoulder 14 adjacent the lower end thereof. The walls of the tip are preferably tapered, as shown, except at the upper end 15 where they extend cylindrically to loosely surround the adjacent end of the body. The tube 13 may be supported fixedly within the tip as by means of a ring plate 16 which is frictionally fitted between the cylindrical walls of the tip.

It is preferred that the tube head 12 be slotted longitudinally at 17 to provide spring sections 18 which are normally bowed outwardly to provide a desired degree of friction against the bushing 11. The tip in which this tube is secured may then be con-

nected separably with the pencil body with which it remains assembled by the tension outwardly exerted by the sections 18 against the bushing in which the same is received.

5 At the upper end of the tube, I provide a constricted neck 19 having internal threads 20 with which the screw threads of the propeller 9 may cooperate. At its lower end the propeller is reduced in diameter in the form of a pin 21.

10 form of a pin 21. Mounted for limited reciprocation with-
in the tube 13 is a lead carrier in the form
of a sleeve 22, the upper and lower ends
23 and 24, respectively, of which are of re-
duced diameter and slotted longitudinally at
25 to provide spring sections. Between the
spring sections at the lower end of the
sleeve a lead C is adapted to be gripped
so as to slide back and forth through the tip
20 of the pencil in response to corresponding
movements of the carrier. The walls of the
tip are thickened at its lower extremity and
bored to provide a cylindrical guideway
which aligns the lead axially with the car-
25 rier. The spring sections at the upper end
of the lead carrier are internally threaded
to cooperate with the threads of the pro-
peller 9 with which they engage with ap-
preciable friction to provide a spring-threaded
30 connection. The reduced lower end of
the lead carrier is receivable within an an-
nular space 26 formed interiorly of the tip
below the stop shoulder 14. I provide stops,
however, for limiting the reciprocations of
35 the lead carrier within the tube 13, so that
the opposite ends of the sleeve will be pre-
vented from engaging and binding with the
parts proximate thereto. For this purpose
the tube may be provided with an inwardly
40 projecting bead 27 which is disposed with-
in an elongated recess 28 extending for a
predetermined distance of the length of the
sleeve. At opposite ends of this recessed
portion of this carrier are formed stop
45 shoulders 29 with which the bead 27 may
alternately engage when the lead carrier is
reciprocated.

Reciprocated. In operation the pencil mechanism performs as follows: Rotation of the pencil body relative to its tip will produce a longitudinal travel of the propeller which also is rotated relative to the operating unit, i. e., the tip, thereby causing the pin 21 to advance the lead C through the pencil. The carrier which is in frictional threaded connection with the propeller tends to rotate therewith so as to advance or retract within the limits determined by the spaced stops 29. Beyond these limits, however, the carrier cannot move so that further rotation of the propeller continues with the carrier remaining stationary and offering an appreciable friction.

The lead may be introduced into the carrier from either of its two ends. If in-

serted through the tip of the pencil, the lead will be gripped by the spring sections at the forward end thereof, and may be pushed back therein approximately to the distance which is represented in Fig. 1. 70 From the uppermost position shown in this figure, the carrier advances rotatively with the propeller between the two stops 29. Hereinafter this motion is referred to as frictionless. When it becomes necessary to 75 advance the lead further, however, the propeller is moved forward again, but rotatively relative to the carrier which is stopped by the upper shoulder 29. The retraction of the lead into the tube a sufficient distance 80 for protection may be brought about by a frictionless reverse operation. In such a limited retractive movement the carrier travels rotatively with the propeller, thus offering no friction thereto. Conversely, 85 when the lead is to be advanced once more to position for use, the carrier advances with the propeller in a frictionless manner up to the point that the upper stop shoulder 29 is engaged. For casual pencil use this 90 range of frictionless movement is all that will be required.

It is possible also to load the operating unit of the pencil with a fresh lead by introducing it thereinto from the upper end. 95 This is accomplished after removing the tip from the pencil and withdrawing the propeller therefrom. Thereafter when the propeller is inserted and screwed into operative position, the lead will be moved forward through the carrier against the friction of its spring sections at the forward end thereof. 100

The present pencil may also be characterized by certain other features which are illustrated in Figs. 1 and 4. I have shown the upper pencil end chambered as at 30 to provide a magazine for extra leads. The closure for this magazine may consist of a multiple jawed retainer 31 carrying an eraser 32, the retainer being supported within a ferrule 33 which extends down over the sides of the pencil adjacent its upper end. Preferably the outer surface of the pencil body is recessed sufficiently to accommodate this ferrule in flush relation with the remainder of the body. The ferrule is detachably fitted to the pencil end so as to permit access to the lead chamber therewithin. The connection which I prefer for holding the ferrule in place is in the form of an indented ornament 34 which presents on the inside of the ferrule a button adapted to engage with a thread 35 which is formed spirally around the surface of the body. The ferrule may be rotatively advanced to a position of rest against an annular shoulder 36 upon the body. It may also be unscrewed for withdrawal from the body, and in this opera- 11 12 13 14 15

tion the eraser held thereby is also removed therewith. Preferably a cap 37 is applied over the eraser and frictionally engaged with the upper end of the ferrule 33. The provision of an ornamental indentation 34, as suggested in Fig. 4, may serve the double capacity of a button for cooperating with the threads 35 to establish connection between the ferrule and body, and of a distinguishing symbol or mark by which the pencil is identified as the product of a particular manufacturer. A button would ordinarily be objectionable because of its marring the external appearance of the pencil head, but by producing the button with an ornamental configuration which does not impair its utility, it is possible to combine into this element two attributes having useful functions.

20 The construction of pencil head just described is particularly advantageous where the body is a moulded bakelite or celluloid product. Such a material, although well adapted for a pencil body, tends to shrink from its original size, or else it cannot be formed uniformly to an exact size. In such circumstances, the pencil head will fail to stay in place satisfactorily if a frictional connection be depended upon. This difficulty is overcome in the present pencil where the head may, if necessary, be loosely fitted in place, since the button in engagement with the thread provides a connection which is positive and unfailing. This is of particular advantage when, as in the present pencil, the cap is frictionally secured to the ferrule because it is then necessary to apply a pulling force to remove the cap preparatory to using the eraser. When, as in previous practice, the ferrule is attached to the body by a frictional connection, the chances are about equal of pulling off the entire head, i. e., the ferrule, cap, and eraser, when only the cap is desired. But by having for the cap a frictional connection and for the ferrule a positive connection, each requiring a different motion for its disestablishment, it is possible to remove the entire head or just the cap, according as is desired.

50 I claim:

1. In combination, a pencil having two relatively rotatable parts, screw means cooperating with both of said parts and adapted to be advanced axially of the pencil in response to relative rotation of said parts to adjust a lead, a lead carrier movable axially through one of said parts, and a spring threaded connection between the carrier and said screw means, substantially as described.

55 2. A pencil having in combination two relatively rotatable parts and a screw means adapted to be moved axially in response to operation thereof, a lead carrier associated with the screw means having a spring threaded connection therewith, and means

for limiting the movements of the lead carrier whereby it may move with the screw means or remain stationary relative thereto, substantially as described.

3. A pencil in which is combined two relatively rotatable parts, screw means associated with said parts and adapted for movement longitudinally of the pencil, and a lead carrier also movable longitudinally within the pencil and open at both ends through one of which the screw means is entered, the lead carrier being adapted to receive a lead when introduced thereinto through either end, substantially as described. 70

4. A pencil in which is combined two relatively rotatable parts, a lead carrier open at both ends reciprocable within the pencil and adapted to receive a lead therein when introduced through either end thereof, and screw means removably connected with the carrier and in cooperation with the relatively rotatable parts adapted to be reciprocated in response to operation thereof, substantially as described. 80

5. A pencil in which is combined two relatively rotatable parts, a lead carrier reciprocable axially of the pencil, screw means also reciprocable within the pencil and cooperating with the relatively rotatable parts thereof so as to be actuated in response to operation thereof, means providing a frictional threaded connection between the screw means and the carrier, and means for limiting the carrier reciprocations through a distance less than the movement range of said screw means, substantially as described. 90

6. A pencil comprising a body portion and a tip portion, a tubular member rigidly carried by said tip portion, a lead carrier within said tubular member, a propeller mounted to rotate with said body portion threaded into said tubular member and threaded into said lead carrier, and means for limiting the longitudinal movement of said carrier within said tubular member. 105

7. A pencil comprising a body portion and a tip portion, a tubular member rigidly carried by said tip portion, a lead carrier within said tubular member, spring members on said lead carrier, a propeller mounted to rotate with said body portion, said propeller having threading connection with said tubular member and threaded into said spring members on said lead carrier, and means for limiting the longitudinal movement of said carrier within said tubular member. 110

8. A pencil having a body and an operating unit frictionally and telescopically connected thereto, a lead carrier having spring means at its upper end movable axially within the pencil, a propeller movable axially through the carrier and connected frictionally and separably thereto by said spring means to move the carrier therewith for a 125

portion only of its travel, and means for limiting the movement of the carrier.

9. A pencil having a body and an operating unit frictionally and telescopically connected thereto, a lead carrier mounted for limited axial movement within the pencil and having spring means at opposite ends, one end of which is provided with screw threads and the other end formed to receive a lead, and a propeller having a screw-threaded frictional connection with the screw-threaded end of the carrier, the propeller being adapted to move a lead both with and relative to the carrier.

10. A pencil having a body and an operating unit frictionally and telescopically connected thereto, said operative unit comprising a tubular lead carrier in the form of a sleeve open at both ends through either open end of which a lead may be inserted, a propeller movable through the carrier, means forming a frictional connection between one end of the carrier and a lead, and means forming a screw-threaded spring connection between the other end and the propeller.

11. In a pencil having a body and a tip frictionally and telescopically connected thereto, a tube carried by the tip and extending within the body, a propeller having sliding non-rotatable connection with the body and threaded into said tube, a tubular lead carrier loosely mounted for limited axial movement within said tube and having a screw-threaded resilient connection with said propeller, and means for frictionally gripping a lead within said carrier, whereby a lead may be advanced or retracted through the tip by the carrier and adjusted relative to the carrier by a relative rotation of the body and tip.

12. A pencil having in combination a body, a tip therefor connected therewith for rotation relative thereto, lead gripping means loosely mounted in said tip for limited sliding movement, means cooperating with both the body and tip and reciprocatable therethrough on rotation of the tip relative to the body, said means having a screw-threaded resilient connection with said lead gripping means to advance or retract the same and to adjust the lead relative to said gripping means upon continued rotation of said tip relative to said body.

JOHN P. LYNN.
